(No Model.)

C. W. SANDY.
ATTACHMENT FOR SAW BUCKS.

No. 461,278.

Patented Oct. 13, 1891.

Fig. 1.

UNITED STATES PATENT OFFICE.

CHARLES WESLY SANDY, OF CLAYSVILLE, KENTUCKY.

ATTACHMENT FOR SAW-BUCKS.

SPECIFICATION forming part of Letters Patent No. 461,278, dated October 13, 1891.

Application filed March 19, 1891. Serial No. 385,675. (No model.)

To all whom it may concern:

Be it known that I, CHARLES WESLY SANDY, a citizen of the United States of America, residing at Claysville, in the county of 5 Harrison and State of Kentucky, have invented certain new and useful Improvements in Attachments for Saw-Bucks; and I do hereby declare the following to be a full, clear, and exact description of the invention, such 10 as will enable others skilled in the art to which it appertains to make and use the same, reference being had to the accompanying drawings, and to letters of reference marked thereon, which form a part of this specification.

15 This invention relates to improvements in saw-bucks.

The object of the invention is to provide a saw-buck with means for holding a log thereon, the saw-buck being attached or fixed to a 20 frame to which a lever is pivoted, said lever carrying a hook which engages with a log, a catch being provided adjacent to the free end of the lever for holding the hook in engagement with a log placed on the saw-buck, as 25 will be hereinafter fully set forth, and particularly pointed out in the claim.

In the accompanying drawings, forming part of this specification, Figure 1 is a perspective view of a saw-buck, showing my invention applied thereto. Fig. 2 is a sectional view taken through the line $x-x$ of Fig. 1.

The frame A consists of two cross-pieces a , to which are rigidly secured longitudinal beams B B, each of which is provided with an 30 upwardly-projecting block located on opposite ends thereof. To the central portion of the beams B B are rigidly secured crossed beams C C, the upper portions of which form the support for the log. The crossed beams 35 or bucks C C are so located that a central space will be left between them.

D refers to a lever which is pivoted to the post or upright b by a pin or bolt d , so that it can be adjusted vertically, as may be desired, and slightly in front of the saw-bucks 40 this lever is provided with a slot e , through which passes the lower end of the hook E, this hook being provided with two or more perforations, so that adjustments can be 45 made through the medium of the pivot-pin f . The inner side of the upright b' is provided

with a ratchet-plate g , and the free end of the lever D carries a catch g' , which engages therewith.

When it is desired to secure a log upon the 55 bucks, the hook is caused to engage with said log, and the operator by pressing one foot upon the end of the lever can depress the same, and by moving the same toward the ratchet-plate and in engagement therewith 60 the lever will be held depressed. Adjustments can be made to suit different sizes of cord-wood. With this device it is not necessary for the operator to use his knee to hold the log upon the saw-buck, and in sawing 65 large logs a crosscut-saw manipulated by two persons may be used.

It will be observed that all the parts of the device are carried by the frame, so that the same can be readily moved from place to 70 place, as may be desired, and that the frame A will give to the saw-buck a solid and fixed foundation and has sufficient weight to hold the whole device rigid against being toppled over when the heavy end of a log projects. 75 It will also be noted that as a clear space is provided between the saw-bucks the log may be sawed between them.

Having thus described my invention, what I claim as new, and desire to secure by Letters 80 Patent, is—

In combination with a saw-buck consisting of a frame made up of longitudinal bars secured to each other and provided with saw-bucks C C, uprights b and b' , one of said uprights having a vertical series of perforations for adjustably securing thereto one end of the lever, a ratchet-plate carried by the opposite upright b' , with which the free end of the lever engages, and a hook E, the upper end 85 of which is adapted to engage with the log placed on the buck, said hook being pivotally secured to the central portion of the lever, the parts being organized substantially as set forth.

95 In testimony whereof I affix my signature in presence of two witnesses.

CHARLES WESLY SANDY.

Witnesses:

W. E. DAVIS,
LESTER BREEZE.
